PORTABLE TRAY ASSEMBLY FOR SOLDERING APPARATUS

Paul V. De Luca, Port Washington, N.Y., assignor to
Porta Systems Corporation, Port Washington, N.Y.

Filed June 9, 1970, Ser. No. 23,390

Term of patent 14 years

Int. Cl. D6—04
U.S. Cl. D33—3

FIG. 1

FIG. 2

FIG. 3

FIG. 1 is a top view of a portable tray assembly for soldering apparatus embodying my new design;

FIG. 2 is a front view of the portable tray assembly for soldering apparatus of FIG. 1; and

FIG. 3 is a side view of the portable tray assembly for soldering apparatus shown in FIG. 1.

I claim:

The ornamental design for a portable tray assembly for soldering apparatus, substantially as shown.
